C. DE W. McNEILL.
HAY PRESS.

No. 410,329.

Patented Sept. 3, 1889.

Charles DeWitt McNeill
by H. G. Anderson,
his Attorney

UNITED STATES PATENT OFFICE.

CHARLES DE WITTE MCNEILL, OF GOLIAD, ASSIGNOR OF ONE-HALF TO
FRANCIS E. HUCK, OF VICTORIA, TEXAS.

HAY-PRESS.

SPECIFICATION forming part of Letters Patent No. 410,329, dated September 3, 1889.

Application filed November 13, 1888. Serial No. 290,748. (No model.)

To all whom it may concern:

Be it known that I, CHARLES DE WITTE MCNEILL, a citizen of the United States, residing at Goliad, in the county of Goliad and 5 State of Texas, have invented certain new and useful Improvements in Hay-Presses; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to hay-presses, and has for its object to simplify and cheapen the construction and render it more efficient in the formation of the hay into bales; and to such ends the invention consists in the construction and combination of parts hereinafter particularly described, and then pointed out in the claims, reference being had to the accompanying drawings, forming a part hereof, and in which—

25 Figure 1 is a side elevation of the press. Fig. 2 is a plan view of the same. Fig. 3 is a vertical cross-sectional view on the line of block R, shown in Fig. 2. Fig. 4 is a central vertical longitudinal section. Figs. 5, 6, and 30 7 are details.

In the drawings, the letter A designates the upright timbers, B the longitudinal timbers, and C the cross-timbers constituting the frame of the press and connected together by 35 bolts applied wherever necessary or desirable. The feed-box E is closed at the bottom and sides, but open at the front for the movement of the plunger and at the rear for the passage of the bale into the tie-box G, which is formed 40 with open or partially-open sides formed by the slats or sectional bars H, as shown. The bottom of the press may be solid or slatted, as desired.

The top of the press is designated by the 45 letter I, and is adjustable up and down, so as to compress the bale vertically more or less, as desired. It is supported by a cross-spring J, secured to it and resting at its ends upon the sides of the press, and is pressed down by 50 suitable means—say by set-screws. The pre-

ferred construction is a set-screw K, passed through a cross-timber L and bearing at its lower end against the block M, attached to the movable top, the screw being provided with a crank N, by turning which the screw 55 will press down that end of the top. The movement of the top is further regulated by another screw P and nut Q. The screw P passes through the cross-timber L', resting on the sides of the press, and bears against a 60 block R, provided with pins S, which press through the timber L' and bear against the block M', so that by adjusting the nut against the washer Q' the block R and its pins will be caused to press down the top. The advantage of the block with the two pins is, 65 that the pins will bear against the top at different points and thus distribute the pressure. While the screws will press down the top, the spring J will exert an upward pressure, so that as the nuts are loosened the spring will draw the top upward. I prefer to locate the screws, which serve as levers, so as to bring one near the discharge end of the tie-box and the other 70 over or adjacent to the feed-box, as a better distribution of pressure is thus obtained. The top at the rear end fits under the cross bolt or brace T, and at its forward end has a hook or catch U hinged or pivoted to it and 75 adapted to project below the top, so as to hold each charge of hay in place and keep it from straggling or falling out of the front end of the feed-chamber. This catch is acted on by a spring V, which may be secured in place by 80 the cross-piece W, and serves to press the catch down and impart to it a yielding pressure. The catch U is shown as supported from the top by an elastic or spring shank U', while the spring-plate V extends over and 85 bears against the top of the catch. The effect of this is to render the catch U elastic and stiff, with power in its shank to lift it as soon as the pressure of the spring-plate V is released, while at the same time the spring-plate 90 will exert a strong pressure on the catch and assist in bracing its spring-shank against pressure from below.

In each side of the feed-box is a series of fingers X, pivoted so as to be thrown out by 95

the charge of hay as it is pressed over them toward the rear end of the feed-box, and adapted to have their ends moved in from the sides of the feed-box after the charge 5 has passed them, so as to form catches or stops to hold the hay in place while the plunger is being drawn back for the next charge. These catches or stops may be acted on by springs *a*, so as to hold their inner ends 10 from the sides of the feed-box. The plunger *Y* of the feed-box is provided on its outer face with two blocks *A'*, constituting jaws, provided with a bolt *B'*, which serves to connect the inner end of the toggle-lever *C'* to 15 the plunger. The inner end of this lever is formed with the tongue *c*, fitting between the blocks *A'*, and formed with a slot *d*, through which the bolt *B'* passes. The inner end of the lever is also formed with the two shoulders 20 *e*, designed, when the toggle is straightened, to bear against the two blocks *A'*, while at the same time the inner end of the tongue will bear against the plunger, thus affording three bearing-points for the toggle-lever, and 25 thus distributing the pressure over the plunger. The outer end of the toggle-lever is likewise provided with two shoulders *f* and with a tongue *c'*, formed with a slot *d'*, so that the tongue *c'* may fit between the jaws *A²* of the 30 main lever *C²*, a bolt *B²* passing through the jaws *A²* and the slot *d'* in the tongue *c'*. The slot *d'* permits the jaws of the main lever, when that lever is straightened, to bear against the shoulders *f* of the toggle-lever, 35 and also allows the end of the tongue of the toggle-lever to bear against the main lever, thus affording several bearing-points for the two levers and distributing the strain over them.

40 Instead of having the jaws of the main lever bear directly against the shoulders *f* of the toggle-lever, I prefer to interpose between them rollers *g*, which will turn on pivots *h*, entering the tongue *c'*, the outer ends of the 45 pivots being journaled in bearing-plates *i*, and between the jaws *A²*, next to the end of the tongue *c'*, I journal a roller *j*, against which the end of the tongue may bear. These 50 rollers very much reduce the friction and take off the wear between the parts, and, besides reducing the strain, cause said levers to move with the greatest ease when manipulated.

The main lever is composed of the diagonally-set pieces *D'*, the connecting cross-piece *D²*, the rearwardly-extending piece *D³*, and diagonally-connecting braces *D⁴*. This lever is fulcrumed to the front cross-piece *E'* of the press by the bolt *F'*, and when the press is 55 supported upon wheels for transportation this lever will be connected to the front axle by the chains *G'*, and will have singletree *H'* attached to its front end. The preferred form of tree is illustrated in Fig. 7, which consists 60 of the tree *H'*, of any suitable construction, sustaining between its ends the pulley *k*,

around which passes the chain *l*, having hooks *m* at its ends, so that when the traces of one horse are hitched to one end of the singletree and the end of the chain nearest thereto 70 and the traces of the other horse are hitched to the other end of the tree and chain an equalizing-doubletree is formed, which causes each horse to pull his own portion of the draft. An apron *n* extends back from the 75 upper end of plunger *Y*, so that when the plunger is pressed forward of the feed-hopper in compressing a charge of hay the apron will form a bottom to the hopper, on which hay may be piled preparatory to dropping it 80 into the feed-chamber. This apron prevents hay from falling down back of the plunger, and, moving with the plunger, allows the accumulated hay to fall into the feed-chamber in front of the plunger as the plunger is 85 moved backward to its position to make another movement to compress another charge of hay.

The follower-blocks *I*, formed with the grooves *J'* for the passage of the binding-wires, subserve the purpose for which such blocks are usually employed in hay-presses.

In operation the hay is placed in the feed-box in separate charges and the plunger forced in upon each charge to press the same 95 to its place, each charge being held to its place by the catches at the top and sides of the box when the plunger is withdrawn, and so the feeding and pressing are repeated until the bale is completed. The formation of the 100 bale is continuous, for as fast as a portion of one bale enters the tie-box another follower-block is placed in the feed-box and the wires inserted in the slots of the follower-block already in the tie-box, so that 105 they can be passed through the slots in the other block as soon as it enters the tie-box. It will be observed, too, that in every quarter-turn of the main lever the plunger is moved in to compress one charge, and in the next 110 quarter-turn is moved out, so as to permit another charge to be introduced, and consequently while the lever is traversing a half-circle one charge is compressed and the plunger brought into position for another 115 charge. The press is not only strong in construction, durable in use, and simple and efficient in operation, but is a continuous baler, and can be used either on the wheels or dismounted, as desired.

I have described what I consider the best details of construction; but it is obvious that changes can be made in some of the parts and in their arrangement without departing from my invention.

Instead of the screw *P* and nut *Q*, I may use any well-known form of lever that will serve the same purpose, and so when I use the term "screw," whether for screw *P* or *K*, I mean to include any well-known form of 130 lever as an equivalent.

I hereby disclaim the spring passing trans-

versely across the roof and having its ends resting on the frame and its central portion depressed and secured to the roof.

Having described my invention and set forth its merits, what I claim is—

1. The combination, with the press-chamber having an adjustable top, of the block R, provided with pins bearing against different parts of the top, the cross-timber L', having 10 apertures for the passage of the pins of the block R, the screw P, passed through said cross-timber and block, and the nut Q, applied to the end of said screw to regulate the pressure of said block and its pins, substantially 15 as and for the purposes set forth.

2. The combination, with the adjustable top, of the spring connected to and suspending said top, and the screws for adjusting the top, one of said screws being located at the discharge end of the tie-box and the other located over or adjacent to the feed-box, substantially as and for the purposes set forth.

3. The combination, with the plunger formed with jaws and the main lever, of the toggle-lever connected at one end with the main lever and at the other end formed with a longitudinally-slotted tongue and shoulders above and below the tongue, said slot being

of a length and said shoulders located at a point with reference to the slot to permit the 30 end of the tongue and the shoulders to bear against the plunger at three points in the compression of the hay, and a bolt passing through the slot and securing the said lever to the plunger, substantially as and for the 35 purposes set forth.

4. The combination, with the plunger and main lever, of the toggle-lever having a tongue formed with a slot permitting a longitudinal play of the lever, a bolt passing through the 40 slot and connecting the toggle-lever and main lever together, friction-rollers mounted above and below the tongue, and a roller mounted between the end of the tongue and the main lever, said rollers being located, substantially 45 as described, to form three yielding points of contact between the toggle-lever and main lever at their adjacent ends when brought together, substantially as and for the purpose set forth.

In testimony whereof I affix my signature in presence of two witnesses.

CHARLES DE WITTE McNEILL.
